BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,099,270.

Specification of Letters Patent. Patented June 9, 1908.

Application filed June 16, 1905. Serial No. 265,591.

To all whom it may concern:

Be it known that I, BURNHAM C. STICKNEY, a citizen of the United States, residing in Elizabeth, in the county of Union and

5 State of New Jersey, have invented certain new and useful Improvements in Type-Writing Machines, of which the following is a specification.

This invention relates to typewriting machines, especially those of the front strike variety, in which type bars are pivoted in an arc below a platen and strike rearwardly against the front side of the platen. In such machines the width of the system of type bars is usually less than the width of the key board. Moreover, the type bars are actuated in a forward and backward direction, while the keys move up and down; and it is one of the objects of my invention to provide a simple and inexpensive mechanism, which is also easily made and assembled, compact, and accessible, for transmitting the downward movements of the keys into the forward and backward movements of the type bars.

The type bars in typewriting machines are usually so heavy that much force is required to put them into quick motion, whereby a shock is given to the fingers upon their contact with the keys.

One of the objects of my invention is to overcome this difficulty, and to cushion the key stroke, so that the touch upon the keys shall be agreeable to the operator, while the type bars may be of sufficient weight and give quick and effective blows.

Another object of my invention is to enable the types, in a front-strike case-shift machine, to lie closely together in the type basket, so that the arc of the type bar segment shall be short, thereby avoiding the necessity of having the types lie across the type bars at unduly great angles, and also gaining other advantages.

45 Other objects and advantages will herein-after appear.

In the accompanying drawings, Figure 1 is a sectional side elevation illustrating the type action of a typewriting machine embodying my improvements. Fig. 2 is a sectional front elevation of the machine, taken in rear of the key board. Fig. 3 is a plan

of the type action. Fig. 4 shows in diagram another form of type action. Fig. 5 illustrates the operation of the same form of the 55 invention.

Against the front side of the usual platen 1, strike type bars 2, each carrying a lower case type 3, and an upper-case type 4, both on one block as shown. These type bars 60 have at their hub ends holes 5, whereby they are hung upon pivots 6; there being an individual pivot for each type bar. Said pivots are formed or provided upon individual hangers 7, having feet 8 to engage 65 transverse grooves 9 formed in the top concave surface of a segment 10, which may be fixed or supported in the machine in any suitable manner. On the under side of said segments are inserted screws 11, which extend up through the segment, each engaging a hanger 7, to hold the same firmly upon the segment. The latter may be provided with a longitudinal groove 12 between the front and back edges, with which may engage 70 projections 13 formed upon the hangers to prevent forward or backward movement of the latter; the screws 11 being midway between the feet 8, to pull the hangers down evenly upon its supports. At Fig. 3, the segment 80 is shown without the groove 12.

In front view, it will be seen that the hangers 7 are wedge-shaped, and that the recess or space 14 between adjoining hangers is just sufficient to accommodate a type bar 85 2, so that adjoining hangers constitute side guides for each type bar. These guides preferably extend from the type bar pivots about one-third of the distance toward the printing point, as at 7^a, and constitute printing 90 guides for the types, so as to dispense with the use of the usual center guide at the printing point. Guide slots for type bars are usually formed in a segment consisting of a single casting; but by using individual 95 hangers of the kind described, it will be seen that the guides may be carried nearer to the platen, because the thinness at the tips of the hangers formed of sheet or bar metal is not an objection, as it would be in the case 100 of brittle cast segments, it being found impracticable to cut thin dividing walls in such segments. Moreover, it will be seen that the space between the hangers is open at the

front, back, top and bottom, all around the type bar, so that there is no opportunity for accumulation of dust and dirt between the hangers; whereas in the case of a segment, one side of the slots is closed, and forms a harbor for dirt, which gradually fills up the slots.

The top portions of the hangers fit in notches or teeth 15 upon the front edge of a curved bar 16, which constitutes a guide rack and prevents lateral vibration of the hangers; locating them accurately with respect to one another, so that they form reliable guides for the type bars. The latter preferably have guide-projections 17, which increase the width of the type bars at the tops of the hangers (Fig. 1), and enable the hangers to prevent the type bars from twisting when delivering blows upon the platen. The rack 16 may be fixed in any suitable manner, as by brackets 18, which connect the ends of said rack to the ends of the segment 10, (Fig. 2).

The types strike upon the front side of the platen, a little above the axial plane thereof, and it will be understood that the platen may be vibrated up and down to enable different types to print; the capital-printing position of the platen being seen in dotted lines at 1^a. The segment and the system of type bars are accordingly mounted somewhat obliquely in the machine, to correspond with the oblique position of the printing point upon the platen.

As seen best at Fig. 3, the hangers, and consequently the type bar pivots 6, do not extend as usual in a straight line across the machine, but in a bowed line, viewed in plan. The hangers and pivots at the middle of the system are forward of those at the sides of the system. Each succeeding hanger, beginning at about the middle of the system, and going toward the sides, is set a trifle in back, and the type bars are of equal length. It will be seen at Fig. 3 that the type system is bowed, and beginning from the middle of the system the types normally lie one a little behind another, those at the extreme sides being rearmost. This compensates for the transverse positions of the types relatively to their type bars, so that the types lie compactly in the type basket 19, and hence the arc of the segment is relatively short, reckoned in degrees and the types are enabled to lie at angles to their type bars which is unobjectionable. That is, the extreme side types extend more nearly longitudinally of their bars than is the usual practice. Each type bar carries its type block at one end, and is pivoted at the other end, the bars preferably of uniform length and the type blocks disposed at gradually increasing angles to the bars as the sides of the system are ap-

proached. The row of type blocks is curved or bowed by setting the type bars with their hangers lengthwise gradually more and more back toward their pivot ends as the sides of the system are approached, to give additional clearance between the adjacent sheets of the type blocks at the sides of the system, the type bars being placed correspondingly closer together. As seen at Fig. 2, the type bars are about 2¹/₄ degrees apart, being uniformly separated throughout the system, and the entire system occupies only a trifle over a quarter of a circle. The extreme types lie at an angle of only about 48 degrees with relation to their type bars, as seen at Fig. 2. This small angle is preferable to the great angles which have heretofore been usual in this style of machine.

It will be understood that it is much easier to construct a typewriting machine, in which all of the bars swing in vertical or nearly vertical planes, than one in which many of them swing in horizontal or nearly horizontal planes, and hence it is a desideratum to have all the type bars in a front strike machine work as nearly vertical as possible. This desideratum is obtained by means of this invention.

It will be seen that the type bars are not of undue length, and that the types in going from normal position to the platen move through the usual distance, so that the touch is not rendered objectionable; while the length of the type bars and their bowed arrangement enables them to be assembled in a segment of about 95 degrees, although the type-bars are 42 in number.

At Fig. 2 it will be seen that the printing point 4 is approximately at the center from which the curve of the row of type bar pivots is struck.

Extending forwardly from the type bars are links 20, connected at 21 to the top ends of a system of sub-levers 22; the latter pivoted at their lower ends at 23 to levers which bear at their forward ends keys 24. The rear ends of said links 20 are pivoted at 25 to reflex arms formed upon the type bars and radiating downwardly and outwardly therefrom; each arm comprising a springy portion 26 extending downwardly from pivot 25, and merging into a long flexible member 27, extending upwardly back of the pivot 25 and past the pivot 5 of the type bar, and joining the hub of the latter at 28. This arm 27 is sufficiently flexible to yield at the key stroke, and is made of springy material. The reflex portion 26 has the effect of increasing the springiness of the arm, being made thin for this purpose, while the pivot 25 is at the proper distance from the type bar pivot 6. In other words, a long arm intervenes be-

tween said pivots, each arm being so springy that it is capable of yielding at each key stroke.

The links 20 move forwardly when the 5 keys are touched, and it will be seen that each link, and hence the direction of the stress, extends directly across or transversely of the spring arm 27 at the initial portion of the printing stroke, so that when the key is 10 touched sharply, said arm yields, owing to the weight or inertia of the type bar. It is easier for the arm 27 to yield, than it is for the type bar to start off at great speed.

It will also be seen by examination of the 15 single type action seen at Fig. 1 in printing position that the links 20 extend in a direction longitudinal of the spring arm 27, and hence have not at this time any appreciable tendency to bend the latter. It will 20 hence be understood that the arm 27, if bent at the initial portion of the key stroke, recovers its normal shape during the stroke and before the completion thereof. In other words, the work originally performed 25 in bending said arm, is utilized during the remainder of the key-stroke in automatically increasing the speed of the type bar. A two-fold object is thus accomplished by cushioning the keys at the initial part of the 30 key stroke and augmenting the speed of the type bar at the final portion of the key stroke. The spring arm 27, in recovering itself during the printing stroke, also tends to cushion the final portion of the key 35 stroke, so that the impetus of the operator's hands is partly absorbed, and less jar is received by the finger when arrested at the completion of the stroke.

The spring-acting arm may otherwise be 40 formed and connected within the scope of the invention, as for instance in the manner shown in Fig. 4 of my application No. 187,362, filed Dec. 31, 1903, and so long as it has the essential operation, it is not necessary 45 that it be formed or provided upon the type bar itself.

It will be seen that, when in normal position, the links 20 extend at about a right angle to a radial line extending from 25 to 50 6, and that at the completion of the printing stroke, said link extends nearly in a line coinciding with said radial line. The distance from 25 to 6 is very great, and hence there is a great loss of leverage during the printing 55 stroke. The key has the greatest leverage upon the type bars at the beginning of the stroke, thus rendering the touch soft for the operator; while the greater part or all of the leverage is lost during the stroke, 60 thus tending to slow down the key action and increase the speed of the type bar, which hence delivers a strong blow upon the platen, and also tending to ease the jar upon the finger at the completion of the key stroke.

Thus it will be seen that a double cushioning 65 effect is produced, by the reduction of leverage during the stroke and by the action of the spring arms.

The U-shaped levers which bear the keys 24, comprise arms 29, which depend from 70 a common fulcrum rod 30, extending across the machine, and suitably supported at its ends in the framework 30^a. These arms 29 are quite long. The rod 30 may be at least as high as the front bank of the keys 24, 75 and is preferably as high as the fourth bank whereby the keys are caused to swing rearwardly as well as downwardly which is a desideratum. The arms 29 are preferably about as long as the distance from said 80 fourth bank to the fulcrum rod 30. There is considerable forward and backward movement of the key levers at the lower ends of said arms 29, or where the sub-lever pivots 23 are provided upon the key levers. These 85 pivots 23 are at or near the bottom ends of said arms 29, upon portions 31 which extend forwardly from arms 29 to the upright key-bearing stems or portions 32.

The sub-levers 22 have fulcrum points 33, 90 at such distances from the pivots 23 as to give the top pivots 21 uniform movements for all the sub-levers; said fulcrum points 33 bearing against the front face of a vertical plate 34, fixed in the machine in any suitable 95 manner, and of sufficient height to accommodate, all of the fulcrum points 33. It will be understood that the points 33 stand at various elevations, owing partly to the difference of the length of the different sub-levers, 100 and partly to the difference in extent of movement of their lower ends; those connected to the rear banks of keys vibrating more than those connected to the front banks of keys. Said sub-levers preferably stand 105 between the arms 29 and the key-bearing stems 32, thus making a very compact and inexpensive mechanism. The pivots 23 and the fulcrum points 33 are nearly in line with the key lever fulcrum 30 at Fig. 1; said 110 pivots 23 vibrating through arcs concentric with the fulcrum 30, and almost concentric with arcs drawn from the respective fulcrum points 33, so that the latter during the key stroke slip but little if any up and down 115 the plate 34, although bearing loosely upon the latter.

The arms 29 may be guided at their upper ends by a comb 35, and at their lower ends by a comb 36 fixed to the rear side of the 120 plate 34; and the forward ends of the key levers may be guided by a comb 37 engaging the arms 31, forward of the comb 36, and fixed in any suitable manner to the framework of the machine. The key levers have 125 projections 29^a which normally rest against the rear edge of the comb 37.

It will be seen at Figs. 2 and 3 that the

4
U-shaped key levers may be parallel throughout, working all in parallel vertical planes; and that the sub-levers may converge from their lower to their upper ends; the width of the system of sub-levers being, at their lower ends, equal to the width of the system of key levers, and at their upper ends equal to the width of the system of type bars. By pivoting the sub-levers at their lower ends to the key levers, and guiding the upper ends of the sub-levers in member 38, the fulcrum points may rest where they will upon the plate 34, and the necessity for making separate fulcrum bearings for the sub-levers is avoided. The lower ends of the sub-levers are bent at 22^a into parallelism with the key levers, and at their upper ends at 22^b into parallelism with the type bars, the links 20 being flat throughout. Thus it will be seen that there is a direct action of each part, without lateral strain at any point, and hence liability of cramping and binding is eliminated, and ease of action is assured.

25 The type bars and their connections may be returned to normal positions by means of draw springs 39, which are connected to the lower ends of the spring arms 27, and caught upon a curved rod 40, which is suitably fixed in the machine, said springs radiating downwardly and outwardly from the type bars, and normally being nearly in line with the type bar pivots 6 so as not to offer much opposition to the starting of the type bars. When the latter are against the platen, the leverage of the springs is greatly increased, as seen at Fig. 1, so as to assist materially in starting the type bars back from the platen.

40 The arms 29 may operate a uniform-motion universal bar 41, extending rearwardly across the system of key levers, and mounted upon a rock shaft 42; the latter connected by an arm 43, link 44, crank 45, and link 46 to a dog rocker 47, having usual dogs 48, 49 to coöperate with the usual rack 50 provided upon the usual platen carriage (not shown). The universal bar 41 may also operate a ribbon-vibrating mechanism (not shown).
50 Since the arms 29 vibrate through different arcs, according to the different distances of the uniformly moving keys from the fulcrum rod 30, I provide upon the rear ends of the arms 29 projections 51 of different lengths, and so placed with reference to the universal bar 41, and with reference to the fulcrums or axes 30 and 42, that the universal bar and hence the dog rocker has uniform movements at all the key strokes.
55 The key levers having the shortest strokes have the longest projections 51 to engage the universal bar plate 41 at points nearest 42 and most remote from 30, and vice versa.

At Fig. 3 it will be seen that the key board is the same as that usually employed

in a thirty-eight key machine, while four additional odd-character keys, numbered 52, are placed in a bank in rear of the usual key board, two at each side of the board, and located between the frequently used keys W and S, E and D, M and I, and O and L, so that the key levers and types stand in the following order, as at Fig. 2: Q A 2 Z W + S 3 X E = D 4 C R F 5 V T G 6 B Y H 7 N U J 8 M @ I K 9 , O & L - P ;

At Fig. 4 I show an upright sub-lever 52^a, fulcrumed between its ends at 53^a to a horizontal fulcrum-link 53. At its lower end the sub-lever is pivoted to the rear end of a link 54, connected to the lowermost rear portion of key-lever 31. The fulcrum-link or idle link 53 is pivoted at 55 to the framework; and the upper end of the sub-lever is pivoted at 57 directly to the type-bar, and follows the movement of the latter, which movement is accommodated by the links 53 and 54, as will be understood from Fig. 5, which shows one type in printing position and one in normal position. It will be seen that Fig. 5 is like Fig. 1, except that the levers 22 and links 20 have been omitted, and that the connections 54, 52^a and 53 have been substituted in place thereof; so much of Fig. 1 as is retained being shown in dotted lines; while the connections seen at Fig. 4 are shown in full lines at Fig. 5.

Other variations may be resorted to within the scope of my invention, and portions of my improvements may be used without others.

Having thus described my invention, I claim:

1. In a typewriting machine, the combination with a platen, of a curved series of type bars mounted to strike upon the front side of the platen, a series of links extending forwardly from the type bars, a series of upstanding sub-levers to whose upper ends said links are connected, and a series of key bearing levers to which said upstanding sub-levers are connected; said key bearing levers fulcrumed at their rear ends in rear of the sub-levers and having portions depending from their fulcrums, and said sub-levers connected to said depending portions at points where the latter have backward and forward movements.

2. In a typewriting machine, the combination with a platen, of a curved series of type bars mounted to strike upon the front side of the platen, a series of links extending forwardly from the type bars, a series of upstanding sub-levers to whose upper ends said links are connected, and a series of key levers to which said upstanding sub-levers are connected; said key levers fulcrumed at their rear ends near the sub-levers, and each key lever extending downwardly from its fulcrum and then forwardly

to the keys, and said sub-levers connected to the key levers below the fulcrums of the latter.

3. In a typewriting machine, the combination with a platen and a curved series of type bars mounted to strike upon the front side of the platen, of a series of links extending forwardly from the type bars, a series of upstanding sub-levers connected to said links, and a series of levers each having a key-bearing stem, a rearwardly extending portion, and a portion or arm extending upwardly to the fulcrum; the fulcrums of the key levers being in rear of said sub-levers and the latter connected to the key-levers at points in or close to said rearwardly extending portions where the key levers move backwardly and forwardly.

4. In a typewriting machine, the combination with a platen, of a curved series of type bars pivoted to strike upon the front side of the platen, a series of links, a series of upstanding sub-levers, to which said links are connected, and a series of U shaped key levers to which said upstanding sub-levers are connected; said key levers fulcrumed at their rear ends in front of the type-bar pivots and having depending portions, and said sub-levers connected to said depending portions at points below the fulcrums of the key-lever where the latter have backward and forward movements.

5. In a typewriting machine, the combination with a platen, of a curved series of type bars pivoted to strike upon the front side of the platen, a series of links, a series of upstanding sub-levers of the first order to which said links are connected, and a series of U shaped key levers to which said sub-levers are connected; said key levers fulcrumed in a single line at their rear ends, each extending downwardly from its fulcrum and then forwardly to the key; and said sub-levers connected to the key levers below the fulcrums of the latter.

6. In a typewriting machine, the combination with a platen and a curved series of type bars mounted to strike upon the front side of the platen, of a series of links extending forwardly from the type bars, a series of upstanding sub-levers connected to said links, and a series of U shaped levers each having a key-bearing stem, a rearwardly extending portion, and a portion or arm extending upwardly to the fulcrum; the sub-levers connected to the key levers at points in or close to said rearwardly extending portions where the key levers move backwardly and forwardly.

60 7. In a front strike writing machine, the combination with a system of U shaped key-levers each comprising a key-bearing stem, a forwardly and rearwardly extending portion and a member extending upwardly from the latter and pivoted or fulcrumed

at its upper end, of a curved system of rearwardly striking type bars having forwardly and rearwardly moving portions, and a system of sub-levers extending up to the type-bars and connecting said forwardly and rearwardly moving portions to the lowermost rear portions of said key levers.

8. In a front strike writing machine, the combination with a system of U-shaped key levers each comprising a key bearing stem, a forwardly and rearwardly extending portion and a member extending upwardly from the latter and pivoted or fulcrumed at its upper end, of a curved system of rearwardly striking type bars having forwardly and rearwardly moving portions, and means connecting said forwardly and rearwardly moving portions to forwardly and rearwardly moving portions of said key levers; said connecting means including a system of sub-levers, and a system of links.

9. In a front strike writing machine, the combination with a system of U-shaped key levers each comprising a forwardly and rearwardly extending portion, and a member extending upwardly from the latter and pivoted or fulcrumed at its upper end, of a curved system of rearwardly striking type bars having forwardly and rearwardly moving portions, and means connecting said forwardly and rearwardly moving portions to the lowermost rear portions of said key levers; said connecting means including a system of upwardly extending sub-levers pivoted at their lower ends to the lower rear portions of the key levers.

10. In a front strike writing machine, the combination with a system of key levers each comprising a key bearing stem, a forwardly and rearwardly extending portion and a member extending upwardly from the latter and pivoted or fulcrumed at its upper end, of a curved system of rearwardly striking type bars having forwardly and rearwardly moving portions, and means connecting said forwardly and rearwardly moving portions to forwardly and rearwardly moving portions of said key levers; said connecting means including a system of sub-levers of the first order pivoted at their lower ends to the key levers below the fulcrums of the latter and extending upwardly and connected at their upper ends to the type-bars.

11. In a front strike writing machine, the combination with a system of key levers each comprising a forwardly and rearwardly extending portion and a member or arm extending upwardly from the latter and pivoted or fulcrumed at its upper end, of a curved system of rearwardly striking type bars having forwardly and rearwardly moving portions, and means connecting said forwardly and rearwardly moving portions to forwardly and rearwardly moving portions of said key levers, said connecting means in-

cluding a system of sub-levers of the first order pivoted at their lower ends to the key levers and extending upwardly therefrom and connected at their upper ends to the type bars by means of rearwardly extending links.

12. In a front strike writing machine, the combination with a system of key levers each comprising a key bearing stem, a forwardly and rearwardly extending portion and a member or arm extending upwardly from the latter and pivoted or fulcrumed at its upper end, of a curved system of rearwardly striking type bars having forwardly and rearwardly moving portions, and means connecting said forwardly and rearwardly moving portions to forwardly and rearwardly moving portions of said key levers; said connecting means including a system of sub-levers connected to the key levers.

13. In a front strike writing machine, the combination with a system of key levers each comprising a key bearing stem, a rearwardly extending portion and a member extending upwardly from the latter and pivoted or fulcrumed at its upper end, of a curved system of rearwardly striking type bars having forwardly and rearwardly moving portions, and means connecting said forwardly and rearwardly moving portions to forwardly and rearwardly moving portions of said key levers, said connecting means including a system of sub-levers; guide combs for the upper and lower ends of said upwardly extending members, a guide comb for said rearwardly extending portions, and returning springs.

14. In a typewriting machine, the combination of a system of key-bearing levers extending rearwardly from the key board, a rod upon which all of said levers are fulcrumed at their rear portions, said levers extending downwardly from said fulcrum rod and then forwardly and upwardly to the keys, a system of sub-levers of the first order having individual fulcrums and connected at their lower ends to the lowermost portions of said key levers at points which move backwardly and forwardly, a curved system of rearwardly striking type bars, and means connecting the upper ends of said sub-levers with forwardly and backwardly moving portions of said type bars.

15. In a typewriting machine, the combination of a system of key-bearing levers extending rearwardly from the key board, a rod upon which all of said levers are fulcrumed at their rear portions, said levers extending downwardly from said fulcrum rod and then forwardly and upwardly to the keys, a system of sub-levers of the first order having individual fulcrums and connected at their lower ends to the lowermost portions of said key levers at points which move backwardly and forwardly, a curved system of rearwardly striking type bars; means connecting the upper ends of said sub-levers with

forwardly and backwardly moving portions of said type bars; means guiding the key levers at their upper ends near said fulcrums, means guiding the key levers at their rear lower portions, and means guiding the forwardly extending portions of the key levers.

16. In a typewriting machine, the combination of a system of key bearing levers extending rearwardly from the key board, a rod upon which all of said levers are fulcrumed at their rear portions, said levers extending downwardly from said fulcrum rod and then forwardly and upwardly to the keys, a system of sub-levers of the first order and having individual fulcrums and connected at their lower ends to the lower portions of said key levers at points which move backwardly and forwardly, a curved system of rearwardly striking type bars; means connecting the upper ends of said sub-levers with forwardly and backwardly moving portions of said type bars; means guiding the key levers at their upper ends near said fulcrums; a plate upon which all of said sub-levers bear or rock, said sub-levers being pivoted at their lower ends to the key levers; and guiding means for the upper ends of said sub-levers.

17. In a typewriting machine, the combination of a system of key-bearing levers extending rearwardly from the key board and fulcrumed at their rear portions, said levers extending downwardly from their fulcrums and then forwardly and upwardly to the keys, a system of sub-levers of the first order and having individual fulcrums and connected at their lower ends to the lower portions of said key levers, a curved system of rearwardly striking type bars, and means connecting the upper ends of said sub-levers with forwardly and backwardly moving portions of said type bars; said sub-levers being pivoted at their lower ends to the key levers; and said key-lever fulcrums and said sub-lever fulcrums being about in line with the points of attachment of said sub-levers to said key levers.

18. In a typewriting machine, the combination of a system of U-shaped key-bearing levers extending rearwardly from the key board, a rod upon which all of said levers are fulcrumed at their rear portions, said levers extending downwardly from said fulcrum rod and then forwardly and upwardly to the keys, a system of sub-levers of the first order and connected at their lower ends to the lower portions of said key levers at points which move backwardly and forwardly, a curved system of rearwardly striking type bars, links connecting the upper ends of said sub-levers with forwardly and backwardly moving portions of said type bars; means guiding the key levers; a plate upon the front face of which

all of said sub-levers loosely bear or rock, said sub-levers being pivoted at their ends to the key levers, guiding means for the upper ends of said sub-levers; and stops for said key-bearing levers.

19. In a typewriting machine, the combination of a system of key-bearing levers extending rearwardly from the key board, a rod upon which all of said sub-levers are fulcrumed at their rear portions, said levers extending downwardly from said fulcrum rod and then forwardly and upwardly to the keys, a system of sub-levers of the first order and having individual fulcrums and connected at their lower ends to the lower portions of said key levers at points which move backwardly and forwardly, a curved system of rearwardly striking type bars, means connecting the upper ends of said sub-levers with said type bars; means guiding the key levers; a plate upon which all of said sub-levers bear or rock; said sub-levers being pivoted at their lower ends to the key levers, and guiding means for the upper ends of said sub-levers; said sub-levers being so proportioned that their upper ends have forward and backward movements of approximately uniform length.

20. In a typewriting machine, the combination with a system of type bars, of a system of key-bearing levers extending rearwardly from the key board and fulcrumed at their rear ends, said levers extending downwardly from said fulcrums and then forwardly to the key-bearing portions, a system of sub-levers connected to the key levers below the fulcrums of the latter and extending upwardly and connected at their upper ends to the type bars; said system of type bars being of less width than said system of key-bearing levers, and said sub-levers converging from their lower to their upper ends.

21. In a typewriting machine, the combination with a system of type bars of a system of parallel key-bearing levers, fulcrumed at their rear ends, said levers extending downwardly from said fulcrums and then forwardly to the key-bearing portions, of a system of sub-levers connected to the key levers below the fulcrums of the latter and extending upwardly and connected at their upper ends by means of links to the type bars, said system of type bars being of less width than said system of key bearing levers, and said system of sub-levers converging from their lower to their upper ends and having approximately the same width at the top as said system of type bars.

22. In a type-writing machine, the combination with a platen, of a curved series of type bars mounted to strike upon the front side of the platen, a series of upstanding sub-levers to whose upper ends said type

bars are connected, and a series of key levers to which said upstanding sub-levers are connected; said key-levers fulcrumed in rear of the sub-levers and having depending portions, said sub-levers connected to said depending portions at points where the latter have backward and forward movements; and said depending portions having projections of varying sizes for operating a universal bar.

23. In a typewriting machine, the combination with a platen, of a curved series of type bars mounted to strike upon the front side of the platen, and having short arms, a series of upstanding sub-levers to whose upper ends said short arms are connected, a series of key levers to which said upstanding sub-levers are connected; said key levers fulcrumed in rear of the sub-levers and having depending portions, and said sub-levers connected to said depending portions at points where the latter have backward and forward movements; and springs connected to the short arms of said type bars and extending radially therefrom.

24. In a typewriting machine, the combination with a platen, of a curved series of type bars mounted to strike upon the front side of the platen, and having short depending arms, a series of links extending forwardly from the type bar arms, a series of upstanding sub-levers to whose upper ends said links are connected, a series of key levers to which said upstanding sub-levers are connected; said key levers fulcrumed in rear of the sub-levers and having depending portions, and said sub-levers connected to said depending portions, and springs connected to the short arms of said type bars and extending radially therefrom and so connected that their leverage upon the type bars increases during the printing movements of the latter.

25. In a typewriting machine, the combination with a key, of a type bar having a spring arm capable of yielding transversely, and a connection from said key to said arm to cause it to yield transversely at the initial part of the printing stroke, but to act longitudinally of said spring arm at the terminal portion of the printing stroke, to relieve the flexing or yielding action of said arm when the type is in printing position.

26. In a typewriting machine, the combination with a key, of a type-operating arm, and an intervening spring arm formed on the type-operating arm and connected to the key, and capable of yielding transversely at the initial portion of the printing stroke of the key, but to act longitudinally of said spring arm at the terminal portion of the printing stroke, to relieve the flexing or yielding action of said arm when the type is in printing position.

27. In a typewriting machine, the combi-

5. In a typewriting machine, the combination with a key, of a type bar having a spring arm capable of yielding transversely, and a connection from said key to said arm to cause it to yield transversely at the initial part of the printing stroke, but to act longitudinally of said spring arm at the terminal portion of the printing stroke, to relieve the flexing or yielding action of said arm when the type is in printing position; the construction and arrangement being such that the leverage of the key upon the type bar gradually diminishes during the printing stroke. 70
15. In a typewriting machine, the combination with a key, of a type bar having a yielding arm, and a key-operated link connected to said yielding arm and normally extending transversely of the latter to cause the same to yield at the initial portion of the key stroke but constructed to change its relative position until said link extends longitudinally of said spring arm, to relieve the flexing or yielding action when the type is in printing position. 75
20. In a typewriting machine, the combination with a key, of a type bar having a yielding arm, and a key-operated link connected to said yielding arm and normally extending transversely of the latter to cause the same to yield at the initial portion of the key stroke but constructed to change its relative position until said link extends longitudinally of said spring arm, (to relieve the flexing or yielding action when the type is in printing position) and about in line with the fulcrum of the type bar. 80
25. In a typewriting machine, the combination with a key, of a type bar having a U-shaped or reflex spring arm, and means connecting the key to said arm to actuate the same transversely and cause it to flex at the beginning of the printing stroke, and lengthwise to relieve the flexing stress at the completion of the printing stroke. 85
30. In a typewriting machine, the combination with a key, of a type bar having a U-shaped or reflex spring arm, and means connecting the key to said arm to actuate the same transversely and cause it to flex at the beginning of the printing stroke, and lengthwise to relieve the flexing stress at the completion of the printing stroke. 90
35. In a typewriting machine, the combination with a key, of a type bar having a U-shaped or reflex spring arm, and means connecting the key to said arm to actuate the same transversely and cause it to flex at the beginning of the printing stroke, and lengthwise to relieve the flexing stress at the completion of the printing stroke. 95
40. In a typewriting machine, the combination with a key, of a type bar having a U-shaped or reflex spring arm, and means connecting the key to said arm to actuate the same transversely and cause it to flex at the beginning of the printing stroke, and lengthwise to relieve the flexing stress at the completion of the printing stroke; the construction and arrangement being such that the leverage of the key upon said spring arm gradually diminishes during the printing stroke. 100
45. In a typewriting machine, the combination with a key, of a type bar having a U-shaped or reflex spring arm, and means connecting the key to said arm to act upon the same transversely to cause it to yield at the beginning of the printing stroke and lengthwise to relieve the yielding action at the completion of the printing stroke; the construction and arrangement being such that the leverage of the key upon said yielding arm gradually diminishes during the printing stroke; and a returning spring whose leverage upon the type-bar gradually increases during the printing stroke. 105
50. In a typewriting machine, the combination with a key, of a pivoted type bar formed or provided with a yielding arm which extends across the end of the type bar, and means for enabling the key to act upon said arm transversely to flex it or cause it to yield at the beginning, and longitudinally to relieve the flexing stress at the end of the printing stroke. 110
55. In a typewriting machine, the combination with a series of keys, of a series of pivoted type bars each formed or provided with a spring arm which is bent reflexly toward the fulcrum of the type bar, and key-operated means acting transversely upon said reflex arms at the beginning and longitudinally at the end of the printing strokes. 115
60. In a typewriting machine, the combination with a series of keys, of a series of pivoted type bars each formed and provided with a spring arm which extends across the end of the type bar and away therefrom, and is then bent reflexly toward the fulcrum of the type bar; and key operated links connected to said reflexly bent arms. 120
65. In a typewriting machine, the combination with a series of keys, of a series of pivoted type bars each formed or provided with a spring arm which extends across the end of the type bar and away therefrom, and is then bent reflexly toward the fulcrum of the type bar; links connected to said reflexly bent arms; and means operating said links in such a manner that normally the latter extend transversely of said type bar arms, but at the printing end of the stroke extend lengthwise of said arms. 125
70. In a typewriting machine, the combination with a series of keys, of a series of pivoted type bars each formed or provided with a spring arm which extends away therefrom and is then bent reflexly toward the fulcrum of the type bar; links connected to said backwardly bent arms; means operating said links in such a manner that normally the latter extend transversely of said type bar arms but at the printing end of the stroke extend lengthwise of said arms; and returning springs attached to said arms and extending radially away therefrom and attached at their opposite ends to a fixed part of the machine, the arrangement of the springs being such that their leverage upon the type bars increases during the printing strokes of the latter. 130
75. In a typewriting machine, the combination with a series of keys of a series of pivoted type bars, each formed and provided with a spring arm which extends across the end of the type bar and away

therefrom, and is then bent backwardly toward the fulcrum of the type bar; links connected to said backwardly bent arms; returning springs attached to said arms and 5 extending radially away therefrom and attached at their opposite ends to a fixed part of the machine, the arrangement of the springs being such that their leverage upon the type bars increases during the printing 10 strokes of the latter; said links extending forwardly from said arms; upstanding levers of the first order to whose upper ends the forward ends of said links are connected, and key levers to which the lower ends 15 of said sub-levers are connected; said key levers fulcrumed above the fulcrums of said sub-levers, and in rear thereof, and extending downwardly from their fulcrums to points of attachment to said sub-levers and 20 then forwardly to their key-bearing portions; said springs serving to return to normal position said type bars, links, sub-levers and key levers.

39. In a front strike writing machine, the 25 combination of a system of rearwardly striking type bars, a segment, and hangers mounted upon said segment and provided with pivots for said type bars, said hangers being wedge-shaped and so mounted that the type 30 bars are guided laterally by adjoining hangers; each type bar with its hanger being detachable from said segment independently of the other hangers.

40. In a front strike writing machine, the 35 combination with a system of rearwardly striking type bars, a segment, hangers mounted upon said segment and having forwardly extending arms which are provided with individual pivots for said type bars, 40 said hangers being wedge-shaped and so mounted that the type bars are guided laterally by adjoining hangers; each type bar with its hanger being detachable from said segment independently of the other hangers.

45. 41. In a front strike writing machine, the combination of a system of rearwardly striking type bars, a segment having grooves, hangers mounted in said grooves and provided with individual pivots for said type 50 bars, said hangers being wedge shaped and so mounted that the type bars are guided laterally by adjoining hangers; each type bar with its hanger being detachable from said segment independently of the other hangers; 55 and screws for fastening the hangers in said segment.

42. In a front strike writing machine, the combination of a system of rearwardly striking type bars, a segment, hangers mounted 60 upon said segment and provided with individual pivots for said type bars, said hangers being wedge shaped and so mounted that the type bars are guided laterally by adjoining hangers; said segment having grooves to receive the bases of said hangers, and screws 65

for fastening the latter in said segment; said screws extending radially up through the segment and threaded into bodies of the hangers.

43. In a front strike writing machine, the 70 combination of a system of rearwardly striking type bars, a segment, hangers mounted upon said segment and provided with individual pivots for said type bars, said hangers being wedge-shaped and so mounted 75 that the type bars are guided laterally by adjoining hangers; each type bar with its hanger being detachable from said segment independently of the other hangers and a fixed rack engaging said hangers upon their rear sides above the pivots of the type bars. 80

44. In a front strike writing machine, the combination of a system of rearwardly striking type bars, a segment, hangers mounted upon said segment and provided with pivots 85 for said type bars, said hangers being wedge shaped and so mounted that the type bars are guided by adjoining hangers; each type bar with its hanger being detachable from said segment independently of the other 90 hangers; and a rack engaging said hangers above the pivots of the type bars; said hangers extending sufficiently far between the type-bar fulcruns and the printing point to serve as printing guides for the type bars. 95

45. In a front strike writing machine, the combination of a system of rearwardly striking type bars, a segment, hangers mounted upon said segment and provided with pivots 100 for said type bars, said hangers being wedge shaped and so mounted that the type bars are guided laterally by adjoining hangers; said hangers guiding the type bars laterally for about one-third of the distance from the type bar pivots to the printing point. 105

46. In a front strike writing machine, the combination of a system of rearwardly striking type bars, a segment, hangers mounted upon said segment and provided with pivots 110 for said type bars, said hangers being wedge shaped and so mounted that the type bars are guided laterally by adjoining hangers; each type bar with its hanger being detachable from said segment independently of the other hangers; the type bar pivots lying one 115 slightly back of another from the middle to the sides of the system, so as to give proper clearance for the double types upon the front ends of the bars.

47. In a front strike writing machine, the 120 combination of a system of rearwardly striking type bars, a segment, hangers mounted upon said segment and provided with pivots for said type bars, said hangers being wedge shaped and so mounted that the type bars 125 are guided laterally by adjoining hangers; each type bar with its hanger being detachable from said segment independently of the other hangers; the type bar pivots lying one slightly back of another from the middle to 130

the sides of the system, so as to give clearance for the double types upon the front ends of the bars; said hangers being of uniform thickness and the type bars lying at uniform intervals.

48. In a typewriting machine, the combination with a system of rearwardly striking type bars mounted in an arc of a circle, of a system of keys in four complete banks, and odd-character keys forming an incomplete fifth bank in rear of said four banks, with their type-bars intervening singly only between adjoining frequently-used type bars.

49. A system of type-bars mounted in an arc of a circle in the usual order and having non-alphabetical odd-character types interposed singly between the types for W and S, E and D, M and I, and O and L, and keys connected thereto and arranged at corresponding intervals in a special incomplete bank; keys being also connected to the remaining type bars and forming a series of complete banks.

50. A segment of type-bars in the usual order and having non-alphabetical odd-character types interposed singly between the W and S, the E and D, the M and I, and the O and L; said odd-character types connected to keys forming an incomplete fifth row in rear of four complete rows of keys connected to the remaining type-bars.

51. In a front strike writing machine, the combination with a platen shiftable up and down almost vertically in a direction slightly forward and backward, of a slightly oblique set of type-bars bowed in plan and striking immediately above the horizontal plane of the platen axis, keys moving downwardly and upwardly, U-shaped levers bearing said keys, upstanding sub-levers between the legs of the key-levers and connected to the lowest portions of the latter, stops engaging projections formed upon the rear legs of the key-levers at their lower ends, links connecting the upper ends of the sub-levers to the type-bars in such a manner that the leverage of the keys upon the type-bars diminishes during the printing strokes, and returning springs for the type-bars and key-levers.

52. In a typewriting machine, the combination with a system of type bars and a fixed vertical plate forward thereof, of upright levers having points to bear at different heights upon said plate, said levers connected at their upper ends to type bars and at their lower ends to key levers.

53. The combination with a system of front strike type bars and a system of levers, each comprising a pendent arm and a key bearing arm extending forwardly from the lower end of said pendent arm, of connection between said forwardly extending arm and said type bars, a plate

upon which said connections have a bearing, and combs extending upwardly and downwardly from said plate to guide said key bearing levers.

54. The combination with a system of yielding type bars each having a yielding spring arm formed thereon, of a system of unyielding key operated devices connected to said yielding arms.

55. A system of type-bars, each carrying at one end a type-block having a plurality of types thereon, and each pivoted at the other end, said bars of uniform length, and the type-blocks disposed at gradually increasing angles to the bars as the sides of the system are approached, and lying in a curved row which is skewed by setting the type-bars lengthwise gradually more and more toward their pivot ends as the sides of the system are approached, to give additional clearance between the adjacent cheeks of the type-blocks at the sides of the system, the type-bars being placed correspondingly closer together; the printing point being approximately at the center from which the curve of said row is struck.

56. A system of type bars, each carrying at one end a type-block having a plurality of types thereon, and each pivoted at the other end to a hanger, said bars of uniform length, and the type blocks disposed at gradually increasing angles to the bars as the sides of the system are approached, and lying in a curved row which is skewed by setting the type-bars with their hangers lengthwise gradually more and more toward their pivot ends as the sides of the system are approached, to give additional clearance between the adjacent cheeks of the type blocks at the sides of the system, the type-bars being placed correspondingly closer together; the printing point being approximately at the center from which the curve of said row is struck.

57. In a typewriting machine, a segment formed on a segment of a skewed annulus, and type bar hangers secured upon said segment in a row which is correspondingly skewed or bowed.

58. The combination of a key, a type bar comprising an integral spring of such strength as to be capable of starting the type bar at moderate speed, but to yield when the key is struck sharply, and means connecting said key to said spring in such a manner that the leverage or purchase of the key upon the spring diminishes during the printing stroke.

59. The combination of a key, a type bar comprising an integral spring of such strength as to be capable of starting the type bar at moderate speed, but to yield when the key is struck sharply, and means connecting said key to said spring in such a manner that the leverage of the key upon

the spring diminishes and disappears during the printing stroke.

60. In a typewriting machine, the combination with a key, of a type bar having an integral arm capable of yielding relatively to the remainder of the type bar at the key stroke, and a connection from said key to said arm; the construction and arrangement being such that at the initial portion of the printing stroke the stress comes transversely of said arm, while at the terminal portion of the printing stroke the stress comes longitudinally of said arm.

61. In a typewriting machine, the combination with a key, of a type-operating lever comprising an integral arm capable of yielding at the printing stroke to permit a relative yielding movement between the key and the type; the construction and arrangement being such that at the initial portion of the printing stroke the stress comes transversely of said arm while at the termination of the printing stroke the stress comes longitudinally of said arm.

62. In a typewriting machine, the combination with a key, of a type-carrying lever comprising an integral pivoted arm capable of yielding relatively to the type arm at the key stroke, a connection extending from the key to said yielding arm in a direction to act upon the latter transversely of its length at the initial portions of the printing stroke, and in the direction of its length at the terminal portion of the printing stroke.

63. In a typewriting machine, the combination with a key, of a type bar having an arm formed thereon capable of yielding at the key stroke, and a key-operated device to exert driving force upon said arm in a direction transversely of the latter at the initial portions of the printing stroke and longitudinally thereof at the final portion of the printing stroke; the construction and arrangement being such that the leverage of said device upon the type bar gradually diminishes during the printing stroke.

64. In a typewriting machine, the combination with a key, of a type bar having formed thereon an arm capable of yielding relatively to the body portion of the type bar at the key stroke, and a key-operated link connected to said arm, and normally extending transversely of the latter; the construction and arrangement being such that during the printing stroke the relation of the parts gradually changes until said link extends longitudinally of said arm.

65. In a typewriting machine, the combination with a key, of a type bar having formed integral therewith an arm capable of yielding at the key stroke, and a key operated link connected to said arm, and normally extending transversely of the latter; the construction and arrangement being such

that during the printing stroke the relation of the parts changes so that said link extends longitudinally of said arm and about in line with the fulcrum of the type bar.

66. In a typewriting machine, the combination with a key, of a type bar comprising a type-carrying arm and a second integral arm capable of yielding at the key stroke, and a key-operated link connected to said second arm, and normally extending transversely of the latter; the construction and arrangement being such that during the printing stroke the relation of the parts changes so that said link extends longitudinally of said second arm, and about in line with the fulcrum of the latter.

67. In a typewriting machine, the combination with a key, of a type bar having an integral arm capable of yielding relatively to the body portion of the type bar at the key stroke; and means connecting the key to said arm in such a manner as to actuate the same transversely at the beginning of the printing stroke and lengthwise at the completion of the printing stroke; the construction and arrangement being such that the leverage of the key upon said arm gradually diminishes during the printing stroke.

68. The combination with a key and a type bar comprising a spring, of an intervening lever, and means including said spring for connecting the lever to the body of said type bar; said connecting means constructed to cause the leverage of the spring upon said lever to increase during the type stroke.

69. The combination with a key and a type bar comprising a spring, of an intervening lever, and means including said spring for connecting the lever to the body of said type bar; said connecting means constructed to cause the leverage of the key upon said lever to decrease during the type stroke, and the leverage of the spring upon said lever to increase during the type stroke.

70. The combination of a key, a type bar pivotally mounted and comprising a resilient integral member, and a link operated by said key and arranged to start said member substantially at right angles to a line extending from said pivot through said member, and draw it substantially into a line between said link and said pivot.

71. The combination of a key, a type bar pivotally mounted and having an extension and a resilient integral member on said extension, and a link arranged to start said member substantially as right angles to a line extending from said pivot through said resilient member, and draw it substantially into a line between said link and said pivot.

72. In a typewriting machine, the combination with a platen and a type bar in front

of said platen, of a key lever mainly in front of said type bar, a pivot for said key lever between the key and the type-bar, upward extensions on said levers having a rearward movement, a universal bar, a type bar lever, and means for operating said universal bar and said type bar lever by the rearward motion of said upwardly extending member.

73. In a typewriting machine, the combination with type bars and connections for operating said type bars, of escapement mechanism, connections for operating said escapement mechanism from a universal bar, key levers entirely in front of said connections and said universal bar, and upwardly extending members on said key levers adapt-

ed to operate said connections on said universal bar.

74. In a typewriting machine, the combination with type-bars, of keys for operating said bars, levers for said keys, said levers having pivots in front of said type-bars, members on said key levers having a rearward thrust, levers for operating said type-bars, and means for connecting the portions of said levers having a rearward thrust to portions of said levers which move mainly forward and backwardly. 25
